UNITED STATES PATENT OFFICE

2,414,350

LATCH FOR VENDING MACHINE DOORS

Raymond Baker, Sr., Upper Darby, Pa., assignor to Horn & Hardart Baking Co., Philadelphia, Pa., a corporation of New Jersey

Original application December 30, 1941, Serial No. 424,881, now Patent No. 2,365,995, dated December 26, 1944. Divided and this application January 11, 1944, Serial No. 517,783

4 Claims. (Cl. 292—269)

1

In my prior application for vending machines, I have described and broadly claimed a novel vending machine wherein novel means are employed to move all of the doors of a vending unit into locking position, and novel means for locking the doors.

My present invention, which is a division of my prior application, aforesaid, Serial No. 424,881, filed Dec. 30, 1941, patented Dec. 26, 1944, No. 2,365,995, relates more particularly to novel latching mechanism for the doors controlled by an attendant in rear of the vending machine to cause all of the doors of a unit to be moved into locking position without shock.

In one type of vending machines used in the "Automats," a bank of vending machines is built up of vending units, arranged side by side to form a continuous wall at a side of a room, and provided with vertically aligned, door controlled delivery openings. Each delivery opening has an individual locking mechanism. Each unit has an article carrier in the form of a rotatable drum having superimposed article receiving compartments, each of which has a combined receiving and delivery opening to register, when in vending position, with a door controlled opening.

Upon the insertion of a coin or coins of proper value into the coin mechanism for a selected compartment and the turning of the handle of its locking mechanism, the door is unlocked and permitted to swing open. Each door is provided with a latch so that, when raised, it will be retained in its raised position. The drum is provided with cams which are effective on rotation of the drum to reset the coin mechanism and lock the doors in their closed position.

The present invention relates to a vending machine of this general character, and comprehends novel latching mechanism, and releasing mechanism therefor.

Other novel features of construction and advantage will hereinafter appear in the detailed description and the appended claims.

For the purpose of illustrating the invention, I have shown in the accompanying drawings a preferred embodiment thereof of which I have found in practice to give satisfactory and reliable results. It is, however, to be understood that this embodiment is typical only and the various instrumentalities of which the invention consists can be variously arranged and organized, and the invention is not limited to the exact arrangement and organization of these instrumentalities as herein set forth.

2

Figure 1 is a sectional plan view of a unit of a vending machine embodying my invention.

Figure 2 is a front elevation of an article carrier.

Figure 3 is a top plan view of an article carrier.

Figure 4 is a side elevation of a door and its latch, the door being shown in its wide open position.

Figure 5 is a side elevation showing the door partially closed.

Figure 6 is a side elevation showing the door closed.

Figure 7 is a side elevation of a slide bar and its adjuncts.

Figure 8 is a side elevation similar to Figure 7, but showing the slide bar and its adjuncts in a different position from that seen in Figure 7.

Figure 9 is a top plan view, showing, more particularly, means for securing the article carrier in vending position.

Figure 10 is a section on line 10—10 of Figure 7.

Figure 11 is a section on line 11—11 of Figure 7.

Similar numerals of reference indicate corresponding parts.

25 Referring to the drawings:

1 designates the frame of a vending machine, embodying my invention.

The frame is provided with a row of superimposed and vertically aligned article delivery openings 2. Each row forms a unit of construction, and in practice a number of units are arranged side by side to form a continuous wall. Each opening 2 is controlled by an individual door 3, pivotally connected at its upper end with the

35 frame and arranged to move to its closed position by gravity. The doors have rollers 4 and have openings 5 in their bottoms to receive locking plungers. Each door 3 has one end of a latch 6 pivotally connected with it. Each latch has an L shaped slot 7, provided with a notch or open recess near the free end of the latch, as at 8, to cooperate with a headed pin 9 fixed to a side wall of a door frame. The bottom wall of the latch has an inclined wall 10 which merges into a stop shoulder 11. The latches are controlled in a

40 novel manner by studs 12 which extend through slots 13 in the frame with proper clearance for the raising and lowering of the studs. The studs 12 are fixed to a bar 14 which is slidable in guides

45 15 fixed to the frame. A handle 16 in the form of a lever is pivoted to a bracket 17 fixed to the frame and is connected by a link 18 with the slide bar 14.

An article carrier, in the form of a drum, having superimposed article receiving compartments

20, is rotatably mounted in the frame so that combined receiving and delivery openings 21 in the drum will register with the door controlled delivery openings of the frame when the drum is in vending position. The drum has a stop member 22 cooperating in a conventional manner with the frame to limit the rotation of the drum.

The drum is locked in its vending position by a spring catch 23, cooperating with a handle 24 carried by the drum to turn it. The drum has on its outer periphery cams 25, similar to those shown in the Cramer Patent No. 1,758,652 to cooperate with locking mechanism similar to that shown in said patent and in the Fritsche Patent No. 1,199,066 and Fritsche No. 1,039,508 to which reference is directed for a detailed description of the construction and operation of such mechanism.

For the purpose of description, it is only necessary to state that the locking mechanism as shown in said patents has for each door a cam slide 26 which moves the locking end of levers 27 into and out of openings 28 in the bottom of a door frame and the openings 5 in the bottom of a door. Each cam slide 26 is connected by a link 29 with its respective, tensioned coin mechanism 30, which, when released, swings laterally to move the cam slide in a direction to cause the unlocking of the door controlling the delivery opening, see Fritsche No. 1,039,508, page 2, line 102 to line 11, page 3. The opening movement of the door is facilitated by springs 31 having one end fixed to the door and their free end bearing against the door frame, see Cramer No. 1,905,083, page 2, lines 120 to 124. The cams 25 on the drum 30 cooperate with cam members 42 of the coin mechanism to reset the coin mechanism and effect the locking of the doors when the drum is turned.

In order to simultaneously lock all of the doors of a unit, the drum has a cam 33 cooperating with a roller 34 on a locking bar 35 slidable in brackets 36 and 46 fixed to the frame. The locking bar is normally retained in its raised position by a spring 37, one end of which is fixed to the bar and the other end to a fixed point such as a bracket 36. The locking bar has locking plungers 38, offset intermediate their ends, and one for each door. The free ends of the locking plungers are bevelled and are adapted to pass into the openings 28 in a door frame and the openings 5 in a door.

The upward movement of the locking bar is limited by a stop 39 on the bar engaging the guide bracket 46. The inward movements of the doors are limited by stops 40 on the door frame.

The coin mechanism has a lever 44 controlling a stop member 45 which in turn controls the passing of a coin through a coin chute into a coin receiver.

The operation will now be apparent to those skilled in this art and is as follows:

We will assume that the compartments of the article carrier have been filled with the articles to be vended, and that the drum is in vending position with the doors locked.

The intending purchaser places a coin or coins in a selected coin slot and turns the handle 41, thereby releasing the coin mechanism, which viewed from the rear swings laterally and moves the cam slide in a direction to unlock the door. The door, when unlocked, swings partially open due to the action of the springs carried by it. The purchaser now raises the door into substantially a horizontal position and the notch in the

slot of the latch receives the headed pin 9 to retain the door in its raised and open position. The purchaser removes the article he has purchased and usually leaves the door in its raised position.

In order to place a fresh article in an empty compartment, it is necessary to turn the article carrier from its vending position to the receiving position, and the doors must be released from their latches. In order to release the doors from their latches, the attendant in rear of the machine presses the handle lever 16 downwardly, thus moving the bar 14 upwardly and causing the studs 12 to raise the free ends of the latches 6 upwardly so that the latches are released by the notches 8 passing above the pins 9.

The doors swing downwardly about half way, being stopped by the walls 10 of the latches. The attendant now releases the handle lever 16, permitting the slide bar to drop. The studs 12 ride up over the walls 10 and engage the shoulders 11. This construction permits the closing of the doors without shock. All of the doors are now in position to be fully closed by the turning of the drum. The spring catch for the article carrier is released and the article carrier is turned from its vending position into its receiving position. During this turning movement, the cams 42 on the article carrier acting against the rollers 4 move the doors into their locking positions. The rollers 4 are positioned near the tops of the doors. The cams 25 on the article carrier cooperate with the cam members 32 of the coin mechanisms reset the coin mechanisms and thereby actuate the cam slides 26 to effect the locking of the doors. The locking bar 35 is in its raised position except when it is lowered by the cam 33. When the vending drum is in vending position, the roller 34 is bearing on the underside of the cam 33, but, as soon as the drum is turned, the roller drops off of the cam and the locking bar moves upwardly to lock all of the doors. This prevents the doors being released and unlocked when the article carrier is turned from its vending position. The latches are released without turning the vending drum.

When the article carrier is in its vending position, the cams 25 engage the cam members 32 so that the stop members 45 of the coin mechanisms are moved out of the coin chutes to permit the coins to pass into the coin receivers.

Having thus described my invention, what I claim as new and desire to secure by Letters Patent is:

1. In a vending machine, a frame having article delivery openings, doors controlling said openings, latches pivoted at one end to said doors and having slots with notches opening into the upper wall of a slot at the inner ends of the slots at the free end of the latches, pins stationary on the frame and extending into the slots and received in the notches when the doors are raised to open position, a latch releasing member slidably mounted and having studs to engage the free ends of the latches to raise such free ends and release their notches from the pins, and means adapted to be actuated by an attendant in rear of the machine to actuate said releasing member.

2. In a vending machine having an article delivery opening, a door controlling said opening and mounted to close when released, a latch to retain said door in open position, and having a cam face, and latch releasing mechanism having

a stud on which the latch rides effective to release said latch, said stud when raised cooperating with the cam face to arrest the closing of the door when partially closed, and when lowered acting to release the latch to permit the door to move to closed position.

3. In a vending machine, a frame having superimposed article delivery openings, doors controlling said openings, latches pivoted at one end to said doors and having slots with notches opening into the slots at one end of the slots, pins on the frame extending into the slots and received in the notches when the doors are raised, a latch releasing member movably mounted on the frame and having studs to engage the latches to release their notches from the pins, said latches having stop walls cooperating with the studs to arrest downward movement of the doors when partially closed, and means to position said releasing member to cause the studs to raise the latches to release their notches from the pins and thereafter when the doors are partially closed arrest down-

ward movement of the doors by engagement of the stop walls with the studs, said positioning means when released allowing said releasing member to drop to permit the stop walls to pass beyond the studs and permit the final closing movements of the doors.

4. In a vending machine, a door frame having an opening through which an article can be removed, a door for said opening, a latch pivoted at one end to said door and having an L shaped slot with a notch, a pin fixed to the door frame and extending into the slot and when in the notch retaining the door in open position, said latch having an inclined stop wall at its bottom merging into a shoulder, and a manually positionable member movable in one direction to raise the latch and release the pin from the notch and to thereafter arrest closing movement of the door by contact with said stop wall, and when moved in the opposite direction permitting the final closing movement of the door.

RAYMOND BAKER, Sr.
